UNITED STATES PATENT OFFICE.

EDWARD E. NAHON, OF NEW YORK, N. Y.

DESIGN FOR A CHAIR.

Application filed October 19, 1927. Serial No. 23,797. Term of patent 14 years.

To all whom it may concern:

Be it known that I, EDWARD E. NAHON, a citizen of the United States, residing at New York, in the county of New York and State of New York, have invented a new, original and ornamental Design for Chairs, of which the following is a specification, reference being had to the accompanying drawing, forming part thereof.

In the drawing—

I claim:

The ornamental design for a chair, as shown.

EDWARD E. NAHON.
